UNITED STATES PATENT OFFICE.

LAURENCE E. TOPHAM, OF SWAMPSCOTT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR OPERATING UPON LEATHER.

1,291,661.

Specification of Letters Patent. Patented Jan. 14, 1919.

Application filed June 29, 1914. Serial No. 847,940.

To all whom it may concern:

Be it known that I, LAURENCE E. TOPHAM, a citizen of the United States, residing at Swampscott, in the county of Essex and State of Massachusetts, have invented certain new and useful Improvements in Machines for Operating Upon Leather; and I do hereby declare the following to be a full, clear, and exact description of the invention, such as will enable others skilled in the art to which it appertains to make and use the same.

This invention relates to machines for operating upon leather, and more particularly to leather or wax thread sewing machines.

In the operation of sewing machines of this class, it is desirable that the operator should be able to stop the machine with the stitch forming devices and work holding parts in any one of a number of predetermined conditions. For example, it is often desirable to stop the machine with the needle and awl out of the work, and the presser foot in work engaging position. This condition of the parts enables the operator either to form one or more stitches by turning the machine by hand, the work being held from displacement by the presser foot, or to lift the presser foot and remove the work from the machine. It is also often desirable to stop the machine with the awl in the work, and with the presser foot lifted from the work, so that the work may be turned about the awl as a fulcrum, as when the machine arrives at a point at which a sharp angle is to be formed in the line of the seam. To permit the removal of the work from the machine the needle and awl should both be out of the work, and the presser foot lifted from the work, and it is therefore desirable that the operator should be able to stop the machine with the parts in this condition. Sewing machines of this class heretofore have been provided with mechanism for stopping the machine at one predetermined point in a cycle of operations and for lifting the presser foot as the machine is stopped to permit the work to be removed. In stopping such a machine at that point in a cycle without lifting the presser foot or in stopping the machine at any other point, the operator has to slow

down and stop the machine by braking the hand wheel manually and then to turn the machine by hand to bring the parts to the desired positions. The stopping and turning of the machine by hand is very tiresome to the operator, particularly when it has to be done repeatedly as is the case in factory work and results in unnecessary loss of time.

One object of the present invention is to provide machines for operating upon leather with mechanism by which the machine may be stopped with the parts thereof in any one of a number of predetermined conditions in a certain and reliable manner without any particular effort on the part of the operator, and which may be easily and conveniently controlled.

Another object of the invention is to provide leather sewing machines with mechanism for stopping the machine and for producing automatically any one of the above conditions of the thread handling and work holding parts when the machine is stopped.

With these objects in view, a feature of the invention contemplates the provision of means for setting the stopping and other mechanism of the machine either while the machine is running or while it is at rest so that when thrown into operation thereafter they will act to produce any desired one of the predetermined conditions when the machine is stopped by the stopping mechanism.

Another object of the invention is to provide leather sewing machines with an improved presser foot lifting mechanism for lifting the presser foot upon stopping the machine at a point in a cycle of operations when the presser foot is normally in work engaging position. With this last and other objects in view, the invention comprises various novel and improved constructions, arrangements and combinations of parts hereinafter described and particularly pointed out in the claims, the advantages of which will be obvious to those skilled in the art.

In the sewing machine embodying the various features of the invention in their preferred forms, the machine is provided with stopping devices by which the machine may be stopped at a point in its cycle of operations when the needle and awl are both out

of the work and the presser foot is in work engaging position, or at a point in a cycle when the awl is in the work and the presser foot is lifted, in each case with the parts 5 in what may be termed a normal condition, or in the positions which they assume at these respective points in each cycle of stitch forming operations. The machine is also provided with mechanism for lifting the 10 presser foot upon stopping the machine at the point in a cycle of operations when the needle and awl are both out of the work and the presser foot is normally in work engaging position. This mechanism is so 15 controlled that it may be rendered active or inactive when the machine is stopped at this point in a cycle. When the machine is stopped with the needle and awl out of the work and the presser foot lifted, what may 20 be termed an abnormal condition of the parts is produced, since the parts are not in the relative positions which they assume during each cycle of operations. The mechanism for stopping the machine and for lifting 25 the presser foot is arranged to be thrown into operation automatically upon disconnecting the main shaft of the machine from the main driving mechanism. The setting mechanism, which is provided for setting 30 the stopping devices and the presser foot lifting mechanism, to cause said devices and mechanism to produce the desired condition of the parts upon stopping the machine, is arranged to be adjusted either while the 35 machine is running or while it is at rest. After the setting mechanism is adjusted, the machine will be stopped with the parts in the desired condition upon the disconnection of the main shaft from the driving 40 mechanism in the usual manner. The machine is stopped and the desired condition of the parts is produced automatically without any further attention on the part of the operator, after the setting mechanism has 45 been adjusted upon the disconnection of the machine from the driving mechanism.

While the invention has been illustrated as embodying devices for stopping the machine at either of two particular points in 50 a cycle of operations of the machine, with the parts of the machine in any one of three particular conditions, it is to be understood that the invention in its broader aspects is not limited to stopping the machine at these 55 points or with the parts in these particular positions, but that it is applicable to stopping the machine at other points and to producing other desired conditions of the parts upon stopping the machine. It is also 60 to be understood that certain features of the invention are not limited to wax thread sewing machines, but may be embodied with advantage in other machines for operating upon leather.

65 The accompanying drawings illustrate a

wax thread sewing machine embodying the various features of the invention in their preferred forms, and the features of the invention will be readily understood from an inspection of the drawings and the following detailed description.

In the drawings: Figure 1 is a view in front elevation of the machine; Fig. 2 is a view in side elevation of the machine looking from the right; Fig. 3 is a view in front elevation of the head of the machine; Fig. 4 is a view in side elevation of the head of the machine looking from the left; Fig. 5 is a view partly in side elevation and partly in vertical section of the head of the machine; Fig. 6 is a view partly in side elevation and partly in vertical section illustrating particularly the parts of the machine below the work support; Fig. 7 is a view in horizontal section taken substantially on the line 7—7 of Fig. 4; Fig. 8 is a detail plan view illustrating certain parts of the presser foot mechanism; Fig. 9 is a detail view in rear elevation illustrating particularly the stopping and presser foot lifting mechanisms; Fig. 10 is a view partly in plan and partly in horizontal section illustrating particularly the stopping and presser foot lifting mechanisms; Fig. 11 is a detail view partly in side elevation and partly in section illustrating the stopping and presser foot lifting mechanisms, looking from the left-hand side of the machine; Fig. 12 is a detail view partly in side elevation and partly in section, illustrating certain parts of the presser foot lifting mechanism; Fig. 13 is a view in vertical section taken substantially on the line 5—5 of Fig. 10; Fig. 14 is a detail sectional view illustrating certain parts of the slow speed clutch and brake mechanism and taken substantially on the line y—y of Fig. 13; Fig. 15 is a detail view in front elevation illustrating certain parts of the controlling mechanism for the stopping and presser foot lifting mechanisms; and Fig. 16 is a diagrammatic view showing a development of the cam groove which forms part of the stopping mechanism.

The invention has been illustrated as embodied in a sewing machine, the sewing mechanism of which has the same general construction, arrangement and mode of operation as that of the machine illustrated and described in applicant's pending application, Serial No. 621,286, filed April 15, 1911. In order to enable the invention to be better understood, however, certain portions of this mechanism will be briefly described in this application. For a full and complete description of the parts of the sewing mechanism of the machine not fully described herein, reference may be had to the said application.

In the drawings the awl is indicated at 2, the needle at 4, the loop taker at 6, the looper

at 8, the thread finger at 10, the work support at 10^a, the presser foot at 12, the take-up at 14 and the tension at 16.

During each cycle of operations of the machine illustrated, starting at a point when the needle and awl are both out of the work, and just before the awl pierces the work, the awl, while the needle remains in retracted position, advances through the work and then moves laterally over into line with the needle to feed the work. The awl then retracts and the needle advances through the hole pierced by the awl following the awl closely through the work. The needle, after receiving a loop of thread in its hook, retracts from the work and remains in retracted position during the remainder of the cycle of operations, while the loop of thread is thrown about the shuttle by the rotary hook and is drawn down into the work by the action of the take-up. The awl, after retracting from the work, moves back to its initial position in the line of feed and remains in this position until the beginning of the next cycle of operations. The awl is retracted from the work during substantially 220 degrees of a revolution of the main shaft of the machine and the shaft rotates through substantially 180 degrees while the needle is advancing through the work receiving the loop of thread in its barb and retracting from the work, the remaining 180 degrees of the revolution being consumed while the needle is in retracted position.

The awl 2 is secured to the lower end of the awl bar 18 which is mounted to reciprocate vertically in suitable guides in the carrier 20. The work is fed by the lateral movement of the awl while the awl is in the work imparted by the lateral movement of the awl carrier. The awl carrier is mounted for lateral swinging movement upon parallel swinging arms 22 and 24. The arms 24 project from a rock shaft 26 and the lateral movements of the awl carrier are imparted thereto by the turning or rocking movements of this rock shaft. The mechanism for actuating the rock shaft comprises a sleeve 28 rigidly clamped to the rock shaft 26 near its rear end and provided with radially extending arms 30. A cam actuated swinging bar 32 (see Fig. 5) is pivotally connected at its lower end with the ends of the arms 30 and carries at its upper end a cam roll 34 which engages in a cam groove cut in the rear face of the cam wheel 36 fixed to the main shaft 38 of the machine. The swinging bar 32 is hung by means of a link 42 from a fixed pivot 40 which is carried by the outer end of the arm 44 fixed to a shaft 46 mounted to turn in suitable bearings in the machine frame. A second arm 48 is secured to this shaft and has a spring actuated plunger 50 mounted upon its outer end which is arranged to engage the teeth of a

segmental plate 52 so as to hold the arm 48, the shaft 46 and the arm 44 in any position in which they may be adjusted. The link 42 and the arm 44 are of substantially the same length and the parts are arranged so that the pivotal connection of the link 42 with the swinging bar 32 is brought into alignment with the axis of the shaft 46 when the awl carrier is in the position which it assumes at the end of the feeding movement of the awl. With this construction the length of feed may be adjusted by adjusting the arm 48 so as to change the position of the fixed pivot 40 and the awl always moves to the same limit at the end of its work feeding movement.

The mechanism for reciprocating the awl vertically, comprises a link 54 pivoted at one end to the awl bar 18 and at the other to the extremity of a swinging arm 56 fixed to the outer end of a rock shaft 58. A second arm 60 (see Fig. 5) is secured to the rear end of this rock shaft and is pivotally connected at its end with the forward end of a reciprocating link 62, the rear end of which is journaled upon a crank pin 64 carried upon the front face of the cam wheel 36. The crank is continuously rotated during the rotation of the main driving shaft 38 and imparts through the mechanism described a vertical reciprocating movement to the awl in timed relation to the lateral movements thereof and to the operations of the other parts of the machine.

The straight hook needle 4 is removably clamped in the upper end of a vertically reciprocating needle bar 66 (see Fig. 6) which is mounted to reciprocate vertically in suitable guides in the frame and is actuated through suitable connections from a continuously rotating crank. The crank operated mechanism for actuating the needle, comprises a bell crank lever 68-70 pivoted at 72, the arm 68 of which is connected by the link 74 with a collar 74^a on the needle bar. The arm 70 of the bell crank lever 68-70 is connected by means of a link 76 with the arm 78 of a second bell crank lever 78-80 pivoted at 82. The arm 80 of the bell crank lever 78-80 is pivotally connected with the forward end of a link 84, the rear end of which is journaled upon a crank pin 86 carried at the outer end of a crank arm 88 formed upon the hub of a gear wheel 90, fixed to the forward end of the horizontal counter shaft 92. By the rotation of the crank pin 86, the bell crank 78-80 and the bell crank 68-70 are oscillated so as to impart suitable reciprocating movements to the needle bar.

The presser foot in the machine illustrated is held yieldingly with a comparatively heavy spring pressure in engagement with the work during the greater part of each cycle of operations so as to hold the

work firmly between the work support and the presser foot during the formation of the stitch but is raised from the work before the work is fed so as to permit the work 5 to be fed forward without resistance between the presser foot and the work support. After the work has been fed, the presser foot is again engaged yieldingly with the work so that it may accommodate 10 itself to any variation in the thickness of the work and is maintained yieldingly in engagement with the work during the remainder of each cycle. The presser foot 12 is secured to the lower end of the presser 15 bar 98 which is mounted to slide vertically in suitable guides 100 and 102 in the frame of the machine. The presser bar is prevented from turning in its sliding bearings by means of an arm 104 extending radially 20 therefrom near its upper end, the outer end of which arm is grooved or bifurcated to engage slidably a pin 106 clamped in the upper guide bracket 100. The mechanism for raising the presser foot automatically 25 during each cycle of operations comprises a collar or sleeve 108 slidingly mounted upon the presser bar and provided with a perforated lug or extension 110 which slides upon a pin 112 fixed in the guide bracket 102. 30 A compression spring 114 coiled about the pin 112 between the head of the pin and the extension 110 acts to hold the sleeve 108 normally down in contact with the upper end of the guide bracket 102. The sleeve 35 108 is formed with a pair of laterally projecting ears 116 between which is pivoted a presser bar lifting arm 118, having a cam shaped inner end for engagement with the presser bar. The cam face at the inner end 40 of this arm is so shaped that when the arm 118 is in lowered position, the inner end of the arm is disengaged from the presser bar but that when the arm is raised from the position in which it is shown in the drawings, the inner end of the arm will be 45 brought into engagement with the presser bar to lock the presser bar to the sleeve 108. When the outer end of the arm 118 is raised, the arm is first turned freely with relation 50 to the sleeve 108 until the cam shaped inner end of the arm is turned into gripping engagement with the presser bar locking it in the sleeve 108, after which the presser bar 98 and the sleeve 108 are lifted together during the continuation of the upward movement of the arm 118. The arm 118 is oscillated by means of a link 120 connecting said arm with an arm 122 fixed to the outer end of a rock shaft 124. The rock shaft 55 124 is provided with a second arm 126 (see Fig. 7) extending from the rear end thereof, which carries a cam roll 128 engaging a cam groove 130 in a cam disk 132 fixed to the forward end of a second continuously rotating counter shaft 134.

To allow the presser foot to be yieldingly engaged with the work after it has been lifted and the work has been fed, the outer end of the arm 118 is depressed to disengage the cam shaped inner end of the arm 70 from the presser bar. The presser foot is then depressed into engagement with the work by its actuating spring accommodating itself to any variation which may have occurred to the work and the sleeve 108 is 75 moved downwardly by the spring 114 into engagement with the upper end of the guide bracket 102. The point at which the presser bar is gripped by the sleeve 108 and the arm 118 will vary with the work engaging position of the presser foot as determined by the thickness of the work so that the presser foot is lifted by the presser foot lifting mechanism substantially a uniform distance from the work regardless of 80 the thickness of the work.

To permit the work to be removed at the completion of the sewing operation or to be adjusted between the presser foot and the work support, it is often necessary or desirable to lift the presser foot at a time when it is normally engaged with the work. To enable the presser foot to be raised at a time when it is normally down in work engaging position, the upper end of the presser bar is offset rearwardly so as to form an upwardly extending plate 136 (see Fig. 8) which is provided with a horizontal forwardly extending ridge or shoulder 138. Within the groove formed between this 95 ridge and the flat upper surface of the main portion of the presser bar engages the rearwardly extending round end 140 of a lifting arm 142 formed on a sleeve 144 journaled on a pin 146 which forms a bearing for one 100 end of a rock shaft 148. The sleeve 144 is provided with recesses 150 in which engage forwardly projecting lugs 152 on the rock shaft 148. The recesses 150 are considerably wider than the lugs 152 so as to 105 allow for lost motion between the sleeve 144 and the shaft 148 when the presser foot is raised and lowered automatically during each cycle of operations. The rock shaft 148 is turned to the right, (Fig. 4) so as to 110 raise the arm 142 and thereby lift the presser bar by the actuation of a bell crank 154 attached to the rear end of the rock shaft and provided with an operating handle 156, by means of which the shaft 148 may be 115 turned to lift the presser foot manually. This bell crank is connected with and actuated by the mechanism for lifting the presser foot automatically upon stopping the machine.

The presser foot is held yieldingly in engagement with the work during each cycle of operations except at the time when it is lifted to permit the work to be fed, by means of a comparatively heavy helical spring 158 120 125 130

- coiled about the rock shaft 148, the forward end of which spring is extended laterally and bears down upon the lifting arm 142, and the rear end of which is engaged by a 5 projection or shoulder on the forward end of a sleeve 160 mounted to rotate upon the shaft 148. This sleeve is formed of independent front and rear sections which are secured against relative rotation by means of the 10 tooth connection 162. Gear teeth 164 are cut in the rear section of the sleeve and are engaged by a rotatable worm 166 having a hand wheel 168 secured thereto by which the worm is turned to adjust the sleeve 160 on the shaft 148 and thereby adjust the tension 15 of the spring 158.
- The tension device comprises a tension wheel indicated at 170 over which the thread passes on its way from the wax pot to the 20 sewing point. This tension wheel is rotatably mounted upon a rod or bar 172 arranged to slide longitudinally in a bracket 174 projecting upwardly from the frame of the machine, and a friction device is provided to retard 25 the rotation of the tension wheel so as to place the thread under tension. The tension wheel friction device is actuated to apply tension to the thread and to relieve the thread of tension in definite timed relation 30 to the operation of the pull-off and the thread locks as will be presently described. The friction device comprises friction disks 176 and 178 arranged upon opposite sides of the tension wheel 170 and arranged to clamp the 35 tension wheel between them. The friction disk 176 is secured to the side of the bracket 174 and the friction disk 178 is slidably mounted upon the bar 172. The right hand end of the bar is reduced so as to form a 40 shoulder 180 which is adapted to be engaged by a corresponding shoulder formed on the interior of the hub of the friction disk 178 and limit the movement of the disk 178 in a left hand direction (Fig. 4) relative to the 45 bar 172. A compression spring 182 surrounding the bar 172 between the disk 178 and a nut 184 threaded on the bar acts normally to maintain the disk 178 engaged with the stop shoulder 180 on the bar except when 50 the bar 172 is drawn to the left, to engage the disk 178 with the tension wheel 170. When the bar 172 is drawn to the left, the disk 178 is first engaged with the tension wheel 170 and the continued movement of the 55 bar then withdraws the shoulder 180 from the disk 178 so that the tension wheel is then clamped between the disks 176 and 178 by the pressure of the spring 182. The 60 resistance offered by the friction disks to the turning movement of the tension wheel 170 furnishes the required tension on the thread as it is drawn over the tension wheel. The bar 172 is thus moved longitudinally to apply the friction device to and to release it 65 from the tension wheel by means of a verti-
- cal lever 186 pivoted at its upper end to the left hand end of the bar 172 and fulcrumed upon the point of an adjustable pin 188 mounted in the bracket 174. The lower end of the lever 186 is formed with a ball 190 70 which engages in a cylindrical recess 192 in a radial extension formed on a sleeve 194 fixed to the forward end of a rock shaft 196. The rock shaft 196 is oscillated to actuate the lever 186 by means of a radially extending 75 arm 198 mounted upon the rear end of the rock shaft. Pivoted upon the outer end of this arm is a bell crank lever 200-202 the arm 200 of which is connected by a link 204 with an arm of the bell crank lever 154. The 80 other arm 202 of the rock shaft is connected by a link 206 with the outer end of an arm 208 extending from a rock shaft 210. The rock shaft 210 is journaled in the frame of the machine and is oscillated by means of a 85 downwardly extending arm 212 (see Fig. 5) secured thereto, which carries a cam roller 214 which engages in a cam groove cut in the rear face of the cam wheel 216 fixed to the main shaft 38. During the normal operation of the machine the toggle formed by the arm 202 of the bell crank lever and the link 206 remains substantially unbroken and oscillatory movements are imparted to the arm 198 and the rock shaft 196 by the oscillation 90 of the arm 208. When the bell crank lever 154 is swung to the right (Fig. 4) to lift the presser foot to allow the work to be removed from the machine the toggle formed by the arm 202 of the bell crank 200-202 and the 95 link 206 is broken and the arm 198 is swung in a direction to release the friction device from the tension wheel and relieve the thread of tension so that the thread may be drawn freely over the tension wheel as the work is 100 removed.
- The pull-off which operates during each cycle of operations of the machine to pull sufficient thread from the supply for the formation of the succeeding stitch, briefly described, consists of a swinging finger 216^a which operates between two thread guiding eyes formed in projections 216^b and 216^c on the upper end of the presser bar, as fully described in the above application. 110
- During each cycle of operations, the thread is locked intermittently between the pull-off and the work and between the pull-off and the tension respectively by front and rear thread locks 218-220 and 242-244. 115 The front thread lock is actuated to lock the thread between the pull-off and the work during the operation of the pull-off in pulling thread from the supply for the succeeding stitch. At this time the rear thread lock is open and during the first part of the stroke of the pull-off arm the tension wheel is released by the friction device so that the thread may be drawn freely from the supply by the pull-off. During the last part 120

of the stroke of the pull-off arm, however, the friction device for the tension is actuated to apply tension to the thread so that the pull-off during the last part of its stroke 5 pulls thread from the supply against the resistance of the tension device. During the operation of the take-up the upper thread lock is closed so as to lock the thread between the take-up and the supply while the 10 lower thread lock is open so that the stitch setting action of the take-up takes place against the upper thread lock.

The front thread lock which acts intermittently to clamp the thread between the 15 take-up and the pull-off comprises a thread roll 218 and a thread clamping shoe 220 which engages the thread as it passes over the thread roll. The shoe 220 is formed upon the arm of the lever 222 pivoted at 20 224, which is oscillated to lock and release the thread by means of an arm 226 mounted upon a rock shaft 228 and having a bifurcated or recessed end in which an arm of the lever 222 engages. The rock shaft 228 25 carries upon its rear end two laterally extending arms 230 and 232 (see Fig. 5) upon which are mounted cam rolls 234 and 236 which run upon two cam surfaces 238 and 240 formed side by side upon the periphery 30 of the cam wheel 36. By the action of these cam surfaces on the cam rolls 234 and 236 the rock shaft 228 is oscillated to open and close the front thread lock.

The rear thread lock which acts intermittently to lock the thread between the tension device and the pull off consists of a thread roll 242 and a shoe 244 which is arranged to engage the thread as it passes over the thread roll 242. The shoe 244 is 35 formed upon the end of an arm 246 fixed to the sleeve 194, the rear thread lock being opened and closed by the oscillatory movements of the sleeve imparted by the mechanism above described. With this construction when the bell crank 154 is actuated to raise the presser foot and release the tension the rear thread lock is opened so that the thread may be drawn freely from the supply.

The shaft 38 constitutes the main shaft 40 of the machine from which all the other parts of the machine are driven during the sewing operation. The counter shafts 134 and 92 are driven from the shaft 38 by means of an upright shaft 252 journaled in 45 the frame of the machine and driven from the shaft 38 by means of a beveled gear 254 fixed to the shaft 38 which meshes with a beveled gear 256 fixed to the upper end of the shaft 252. The shaft 134 is driven from the shaft 252 by means of a spiral gear 258 fixed to the shaft 252 which meshes with a corresponding gear 260 fixed to the shaft 134. The driving connection between the shafts 252 and 92 consists of the beveled gear 262 fixed to the lower end of the shaft 45

252 which meshes with a beveled gear 264 fixed to the shaft 96. The driving connection between the shaft 38 and the shaft 92 drives the shaft 92 in the opposite direction from the direction of rotation of the shaft 38 and the gears are so proportioned that the shaft 92 is driven at substantially the same speed as the shaft 38.

During the sewing operation the machine is driven by means of the driving shaft 266 (see Figs. 1 and 2) mounted in bearings 268 and 270 in the base of the machine and belted to the shaft 38 by means of a belt 272 passing about a pulley 274 on the shaft 266 and the pulley 276 fixed to the end of the shaft 38. The shaft 266 is mounted so that it may be swung in a vertical plane about a horizontal axis located near the left hand end of the shaft to tighten and loosen the belt 272 about the pulleys 274 and 276 and thereby connect the shaft 38 with and disconnect it from the driving shaft 266. To this end the bearing 268 for the shaft 266 is mounted upon trunnions 278 carried by the arms of a yoke 280 formed at the upper end of a bar 282 secured in brackets 284 on the frame of the machine. The bearing 270 for the shaft 266 is also mounted upon bearing pins or trunnions 286 carried by the arms of a yoke 288 formed at the upper end of a slide 290 mounted to slide in guide brackets 292 on the frame of the machine. The right hand end of the shaft 266 is normally supported in position to maintain the belt 272 in loosened condition by a tension spring 294 attached at its upper end at 296 to the frame and at its lower end to the bearing 270. The right hand end of the shaft 266 is depressed to tighten the belt 272 and thereby establish a driving connection between the shaft 266 and the shaft 38 by means of a treadle 298 pivoted at 300 and having an arm 302 connected by a link 304 with the lower end of the slide 290. The numeral 306 indicates a power shaft from which the machine is driven by means of a belt 308 passing about a pulley 310 fixed to the shaft 266 and about a pulley 312 fixed to the shaft 38.

The mechanism for stopping the machine 115 is applied to the countershaft 92 of the machine, the slow speed clutch by which the machine is slowed down to a predetermined speed, and then driven in a forward direction to stopping position, and the brake by 120 which the machine is finally stopped, being carried by and acting directly upon said shaft. The slow speed clutch mechanism comprises a slow speed driving pulley 314 which is loosely mounted on the shaft 92 and 125 is constantly driven at a definite slow speed in the same direction as the normal direction of rotation of the counter shaft by means of a belt 316 passing about said pulley and about a pulley 318 mounted on the 130

power shaft 306. In the construction illustrated, referring particularly to Fig. 13, the pulley 314 is mounted upon a bushing 320 which is driven tightly into the pulley and which is journaled upon a sleeve 322 fixed to the shaft 92. The pulley is held from movement longitudinally of the shaft between a flange 324 on the sleeve 322 and a washer 326 secured to the end of the shaft 92 by a screw 326^a. The driving member 328 of the slow speed clutch is secured to the pulley 314 by screws 330. The driven member 334 of the slow speed clutch is formed upon a flange projecting from a sleeve 336 which is mounted to rotate with the shaft 92 but is movable longitudinally of the shaft to engage and disengage the members of the clutch. The sleeve 336 also carries a brake member 338 formed on a second flange projecting therefrom which is arranged to engage a fixed brake shoe 340 on the frame of the machine. The sleeve 336 during the normal operation of the machine is held in an intermediate position relative to the driving member 328 of the slow speed clutch and the brake shoe 340 so that both the clutch and the brake are disengaged. In the construction illustrated, the sleeve 322 is formed with a cylindrical hollow boss 342 in which is threaded a thimble 344. A pin or stud 346 secured at one end in the flange upon which the clutch member 334 is carried passes through registering openings in the ends of the chamber formed by the boss 342 and the thimble 344 and a coiled spring 348 is coiled about the pin 346 and interposed between washers 350 and 352 on the said pin. A collar 354 is mounted on the pin 346 between the washer 352 and the flange on the sleeve 336 in which the pin is secured. The outward movement of the washer 350 is limited by its engagement with the head of the pin 346 and the movement of the washer 352 is limited by its engagement with the collar 354. The parts are constructed and arranged so that when the sleeve 336 is in an intermediate position on the shaft with the slow speed clutch members and the brake members disengaged the washers 350 and 352 are in their limiting positions on the pin 346 in engagement respectively with the head of the pin and the collar 354 and engage the ends of the chamber formed in the boss 342 and the thimble 344. With this construction the sleeve 336 is yieldingly held in position longitudinally of the shaft but the sleeve may be moved in either direction against the tension of the spring 348 to engage the clutch or to engage the brake.

60 As above stated, the sleeve 336 is mounted to rotate with the shaft 92 and to this end is secured to the sleeve 322 which is keyed to said shaft. In order to furnish a reliable driving action between the sleeve 336 and the sleeve 322 the sleeve 336 is formed with ra-

dially projecting shoulders 356 which engage corresponding shoulders 358 on the sleeve 322 as shown in Fig. 14.

When the stopping mechanism is rendered operative the sleeve 336 is shifted in one direction longitudinally of the shaft 92 at a definite point in a cycle of operations to engage the slow speed clutch, which first acts as a brake to slow down the speed of the shaft to the speed of the driving member of the clutch, and then drives the shaft forward at slow speed to stopping position. The sleeve 336 is shifted in the opposite direction to disengage the clutch and engage the brake to stop the shaft at either of two predetermined points in the rotation of the shaft, so that the machine may be stopped at either of two definite points in a cycle of operations.

The mechanism for controlling the engagement of the slow speed clutch and the engagement of the brake comprises a cam groove 360 formed in the sleeve 336 in which engages a cam roll 362 mounted at the end of the arm 364 of a bell crank lever which is pivoted upon the vertical shaft 366. The other arm 368 of the bell crank lever is formed with a recess 370 arranged to receive the upper end of a locking bolt 372 mounted to slide vertically in the rear end of a lock bolt carrier 374 having a cylindrical shank 376 which is arranged to slide horizontally in a suitable guide in the frame of the machine. A rod 378 having a head 380 passes through a perforation in a web 382 at the end of the guide bore in which the shank 376 of the lock bolt carrier is mounted and the lock bolt carrier is yieldingly held in its normal position in the frame by means of a spring 384 coiled about the rod 378 and engaging at one end the end of a chamber in the lock bolt carrier in which it is seated and at the other a collar 386 on the rod 378. The forward movement of the lock bolt carrier under the influence of the spring 384 is limited by the engagement of a lug 388 projecting upwardly from the carrier with an adjustable abutment screw 390 mounted in the frame of the machine.

During the normal operation of the machine the lock bolt is held down out of engagement with the recess 370 in the arm 368 of the bell crank lever so that the lever is normally oscillated idly by the cam. When the lock bolt is moved upwardly to engage the upper end thereof with the recess 370 in the arm of the bell crank lever, the bell crank lever is locked to the lock bolt carrier, and through the co-operative action of the cam groove 360 and the cam roll 362 the sleeve 336 is shifted longitudinally of the shaft 92 to engage and disengage the slow speed clutch.

The lock bolt 372 is mounted to slide vertically in the rear end of the lock bolt carrier and is moved upwardly to engage

its upper end with the recess 370 in the arm 368 of the bell crank lever by means of a coiled spring 392. The lock bolt is held down during the normal operation of the 5 machine through a connection with the treadle and is released and moved upwardly by the spring when the treadle is released to disconnect the main shaft of the machine from the main driving mechanism. In 10 the illustrated construction a block 394 is fixed to the lower end of the lock bolt and carries a shaft 396 on which is pivoted a latch 398 arranged to engage beneath the shoulder 400 upon the rear end of the lock bolt carrier. 15 An arm 402 is pivoted upon the shaft 396 and is provided with a hub having a recess 404 in which engages a projection 406 upon the hub of the arm 398. The recess 404 is somewhat wider than the projection 406 20 so that there is considerable lost motion between the arm 402 and the latch 398. The arm 402 is pivotally connected by means of a pin or bolt 406^a with the upper end of a rod 408 which at its lower end is connected 25 with the yoke 288. When the treadle is depressed to start the machine the end of the latch 398 brings up against the outer face of the shoulder 400 and slides downwardly along said face until the locking pin is released 30 from the recess in the arm of the bell crank lever when the latch 398 snaps in beneath the shoulder 400. When the treadle is released the arm 402 swings upwardly some distance before the latch 398 35 is disengaged from beneath the shoulder 400 and the locking pin thereby released so as to insure that the main driving mechanism shall be disconnected from the machine before the locking pin is moved upwardly into 40 engagement with the recess 370 in the arm 368 of the bell crank lever.

The machine is illustrated in the drawings with the parts in the positions which they assume when the machine has been 45 stopped by the stopping devices at a point in a cycle of operations when the needle and awl are out of the work and the presser foot is normally in work engaging position. The stopping mechanism is arranged to stop the 50 machine at this point in a cycle of operations, or at a point about 70° later in a cycle of operations when the awl is in the work and the presser foot is lifted.

Fig. 16 shows the formation of the cam 55 groove 360 as constructed in the present embodiment of the invention. As will be noted from an inspection of this figure the cam groove is formed with a portion 410 substantially parallel with the plane of rotation of the sleeve 336 and located adjacent the right hand end of the sleeve looking from the front of the machine. Leading from the portion 410 of the groove is an incline 412 which connects the portion 410 60 of the cam groove with the portion 414

thereof. The portion 414 of the cam groove also is formed substantially parallel with the plane of rotation of the sleeve 336, but is located adjacent the left hand end of the sleeve. From the portion 414 of the cam 70 groove extends a relatively short incline 416 the direction of inclination of which is opposite to that of the incline 412 and which leads into a portion 418 of the groove constructed parallel with the plane of rotation 75 of the sleeve. The portion 418 of the groove is connected with the portion 410 thereof by a second relatively short incline 420 similar to the incline 416. The locking pin is engaged with the recess in the arm 368 of 80 the bell crank lever at a point in the rotation of the shaft 92 while the roll 362 is passing through the portion 410 of the cam groove 360. When the bell crank lever is locked to the lock bolt carrier by the lock 85 bolt and the roll 362 arrives at the incline 412 in the cam groove 360, the sleeve 336 is moved longitudinally of the shaft 92 to engage the slow speed clutch and the clutch 90 remains engaged while the roll 362 is passing through the portion 414 of the cam groove. During this period of engagement 95 of the clutch the shaft 92 is slowed down to the speed of the driving member of the clutch and is then driven forward at slow 100 speed by the driving member. The sleeve 336 is moved in the opposite direction longitudinally of the shaft to disengage the slow speed clutch and engage the brake while the roll 362 is passing from the portion 414 to 105 the portion 410 of the cam groove.

When the cam roll 362 is passing through the incline 412 in the cam groove 360, the sleeve 336 is moved longitudinally of the shaft 92 to engage the members of the slow 110 speed clutch, and then during the remainder of the progress of the roll through the incline the bell crank 364-368 is swung on its pivot, moving the lock bolt carrier toward the rear of the machine against the tension 115 of the spring 384. To enable the sleeve 336 to be shifted in the opposite direction a distance sufficient to disengage the slow speed clutch and engage the brake at some point during the passage of the roll 362 from the 120 portion 414 of the cam groove to the portion 410 thereof, devices are provided for preventing the return of the lock bolt carrier to its initial or normal position while the roll 362 is passing from the portion 414 of the cam groove to the portion 410. The inclines 416 and 420 in the cam groove 360 are arranged at definite points in the periphery 125 of the sleeve 336, and the devices for preventing the return of the lock bolt carrier to its initial position are arranged to stop the lock bolt carrier in substantially its rearmost position, or in a position intermediate its rearmost and its initial position, so as to render either of the inclines 416 and 130

420 alternatively effective to shift the sleeve 336 to disengage the slow speed clutch and engage the brake to stop the machine in either of two definite positions. The devices for preventing the return of the lock bolt carrier consist of the pawls 424-426 pivoted side by side upon the stud 428 and arranged to engage the head of an abutment or contact stud 430 adjustably mounted in the lock bolt carrier. It will be noted from an inspection of Fig. 11 that the pawl 424 is considerably longer than the pawl 426. These pawls are arranged to be rendered operative alternatively to control the point in a cycle of operation at which the machine is stopped, as will be presently described. During the normal operation of the machine the pawls are swung downwardly from the position in which they are shown in the drawings, their left-hand ends (Fig. 11) resting beneath a portion of the lock bolt carrier below the contact stud 430. When, after the stopping mechanism has been thrown into operation, the lock bolt carrier is moved toward the rear of the machine by the action of the incline 412 on the roll 362 subsequent to the engagement of the slow speed clutch, one or both of the pawls are swung upwardly into operating position in front of the contact stud 430. The pawl 424 is provided with a laterally extending stud 438 which rests in a recess 440 in the lower side of the pawl 426, and is engaged by the rearwardly projecting end of a spring 442 coiled about the stud 428, the other end of which is engaged beneath a portion of the frame, this spring tending to swing the long pawl upwardly into operating position. This construction enables the long pawl to be controlled by the short pawl and allows the short pawl to be swung upwardly into operating position independently of the long pawl. The short pawl 426 is connected with the rod 408 by a link 444 having a slot 446 in which engages the pin or bolt 406^a which connects the rod 408 with the arm 402. This connection between the link 444 and the rod 408 allows the rod to move upwardly to release the locking pin while the pawls lie beneath the lock bolt carrier. The short pawl is swung upwardly into operating position by means of a tension spring 448 attached at one end to the pin 406^a and at the other to an extension on the link 444. When the treadle is depressed to start the machine, both pawls are swung downwardly from the positions in which they are shown in the drawings through their connection with the rod 408, and the lock bolt carrier is then moved forwardly to its normal position by the spring 384. When the machine is to be stopped at a point in a cycle of operations when the needle and awl are both out of the work and the presser foot is in work engaging position, both pawls are allowed to rise

in front of the stud 430 upon the rearward movement of the lock bolt carrier. The carrier, however, is caught by the long pawl 424, the end of which projects some distance to the rear of the short pawl. The long pawl is preferably constructed to stop the lock bolt carrier in substantially its rear-most position. When the long pawl is acting to hold the lock bolt carrier from forward movement in the frame, and the roll 362 engages the incline 416 in the cam groove 360, the sleeve 336 is shifted on the shaft 92 to disengage the slow speed clutch and engage the brake to stop the machine. The parts are arranged and timed so that the roll 362 engages the incline 416 just before the machine arrives at stopping position with the needle and awl out of the work, and that the machine is stopped preferably just after the roll 362 reaches the portion 418 of the cam groove when the machine has arrived at the desired point in the cycle. When the machine is to be stopped at a point in a cycle of operations when the awl is in the work and the presser foot is lifted, the long pawl is held down out of operative position upon the rearward movement of the lock bolt carrier. When the long pawl is inoperative, the lock bolt carrier is caught by the short pawl after it has moved forward some distance from its normal position. The short pawl is arranged to stop the forward movement of the lock bolt carrier after said carrier has moved forwardly during the passage of the roll 362 through the incline 416 of the cam groove 360, but before the roll arrives at the incline 420 in said groove. When the short pawl only is operative, the incline 416 in the cam groove 360 will therefore not be effective to shift the sleeve 336 to disengage the slow speed clutch and engage the brake. During the passage of the roll 362 through the incline 420 in the cam groove, the lock bolt carrier then being held by the short pawl from further forward movement, the sleeve 336 will be shifted to disengage the slow speed clutch and engage the brake to stop the machine. The parts are timed so that the roll 362 engages the incline 420 in the cam groove 360 just before the machine arrives at stopping position at a point in a cycle of operations when the awl is in the work and the presser foot is lifted, and the machine is stopped preferably just after the roll 362 reaches the portion 410 of the cam groove, which occurs when the machine has arrived at the desired point in the cycle.

The long pawl is provided with a forwardly projecting lug or tail 450, and is prevented from rising into operative position when the machine is to be stopped at a point in a cycle of operations when the awl is in the work and the presser foot is lifted, by the engagement of a sector-shaped projec-

tion 452 formed on a shaft 454 mounted in a bearing 456 in the frame with the under side of the tail 450. The shaft 454 is provided with a handle 458 by which the shaft 5 may be turned in its bearings to adjust the sector-shaped projection 452 in different positions. When the machine is to be stopped at a point in a cycle of operations when the needle and awl are out of the work and the 10 presser foot is in work engaging position, the handle 458 is adjusted in a horizontal position, as shown in the drawings. This adjustment of the shaft 454 locates the sector-shaped projection 452 in the position 15 shown in Fig. 15, so that it does not interfere with the rising of the long pawl into operating position when the stopping mechanism is thrown into operation. With this adjustment of the sector-shaped projection 20 452, both pawls swing upwardly together when, after the stopping mechanism is thrown into operation, the lock bolt carrier moves toward the rear. The lock bolt carrier is stopped, however, by the long pawl 25 in substantially its rearmost position, and the sleeve 336 is shifted on the shaft 92 to disengage the slow speed clutch and engage the brake to stop the machine at the desired point in the cycle. When the machine is 30 to be stopped at a point in the cycle of operations when the awl is in the work and the presser foot is lifted, the handle 458 is swung downwardly substantially 45° from the position shown in the drawings. This adjustment 35 of the handle 458 locates the sector-shaped projection 452 in a position such that its right-hand face (Fig. 15) lies substantially in a horizontal plane. When the projection is thus adjusted, and the stopping 40 mechanism is thrown into operation, the long pawl is prevented from rising when the lock bolt carrier is moved to the rear by the engagement of the tail 450 of the pawl with the projection 452, and the short pawl rises 45 alone into operating position in front of the abutment stud 430. The lock bolt carrier is then stopped by the short pawl in its intermediate position, and the sleeve 336 is shifted upon the shaft 92 to disengage the 50 slow speed clutch and engage the brake to stop the machine at the desired point in the cycle with the awl in the work and the presser foot lifted.

The mechanism for lifting the presser foot 55 upon stopping the machine at a point in a cycle of operations when the needle and awl are out of the work, and the presser foot is normally down in work engaging position, comprises a lever 460 pivoted upon a shaft 462, and connected by a rod 464 with the laterally extending arm of the bell crank lever 154. When the lever 460 is swung downwardly about the shaft 462, the bell crank lever 154 will be swung in a direction to lift the presser foot through the

mechanism hereinbefore fully described. Pivoted co-axially with the lever 460 on the shaft 462 is a cam lever 466 carrying a cam roll 468 which engages in a cam groove 470 cut in the right-hand face of the gear 264. 70 To operatively connect the cam lever 466 with the lever 460 a dog 472 is fixed upon a shaft 474 mounted to turn in a downwardly extending arm of the lever 460, the forward end of the dog being arranged to engage to 75 the rear of the shoulder 476 formed on the lever 466. When the end of the dog 472 is engaged behind the shoulder 476, the lever 460 is actuated in a direction to lift the presser foot by the rearward swinging movement of the cam lever 466. A tension spring 478, attached at one end to the lever 460 and the other end to the dog 472, tends to swing the dog upwardly into a position behind the shoulder 476. While the presser 80 foot lifting mechanism is inoperative, the dog 472 is maintained in a position below the shoulder 476, so that the cam lever 466 vibrates idly. When the presser foot lifting mechanism is to be thrown into operation, the dog 472 is released, and as the lever 466 swings forward the dog is swung upwardly by the spring 478 to bring the end of the dog to the rear of the shoulder 476. 85 A retaining device is provided for maintaining the dog 472 in an inoperative position below the shoulder 476 while the machine is running; which acts to release the dog when the stopping mechanism is thrown into operation. This retaining device 90 consists of a lug 482 projecting laterally from the lock bolt carrier, and arranged to engage the rear face of the upper end of an arm 480 fixed to the shaft 474 upon which the dog 472 is mounted. This lug acts to maintain the dog 472 in the position shown in 95 Fig. 12 while the stopping mechanism is inactive. After the stopping mechanism is thrown into operation, and the lock bolt carrier is moved rearwardly as above described, the lug 482 releases the arm 480. A second retaining device is provided, however, for maintaining the dog 472 in inoperative position relative to the cam lever 466, and is arranged to be moved into and 100 out of retaining position by the adjustment of the setting mechanism by which the point at which the machine is stopped by the stopping devices is controlled. The position of this retaining device is controlled 105 through connections from the mechanism for setting the stopping devices. When the setting mechanism is adjusted to cause the stopping devices to stop the machine at a point in a cycle of operations when the awl 110 is in the work and the presser foot is lifted, the retaining device is located in retaining position so as to maintain the dog 472 in inoperative position and thereby render the 115 presser foot lifting mechanism inactive. 120

125

130

When the setting mechanism is adjusted to stop the machine at a point in a cycle of operations when the needle and awl are out of the work and the presser foot is normally in work engaging position the retaining device may be left in retaining position or may be moved out of retaining position by the adjustment of the setting mechanism. This second retaining device consists of a 5 retainer block 484 secured by a clamping screw 486 to the end of a longitudinally movable rod 488, the retainer block having a downwardly projecting end which is arranged to engage the rear side of the arm 480. The rod 488 on which the retainer block is mounted is arranged to slide in a guide in a projection 490 on the shaft 462, and is pivotally connected at its forward end with a lever 492 pivoted on the stud 20 494. The lower arm of this lever is provided with an inwardly projecting end 496 (Fig. 15) which engages in a cam groove 498 formed in the shaft 454. The retainer block 484 is shown in the drawings in position to maintain the dog 472 out of operative relation to the lever 466, and thereby to maintain the presser foot lifting mechanism inoperative. The cam groove 498 in the shaft 454 is so constructed that when 25 the setting handle 458 is adjusted in a horizontal position, or when it is set in a position 45° below the horizontal, the retainer block will be held in a position to maintain the dog 472 inoperative, but that 30 as the handle 458 is swung upwardly substantially 45° from a horizontal position, the lever 492 is actuated to move the retainer block 484 to the rear out of retaining position relative to the arm 480. This last 35 adjustment of the setting handle moves the projection 452 out of engaging position relative to the projection or tail 450 on the long pawl, so that the lock bolt carrier will be stopped by the action of the long pawl 40 when the stop mechanism is thrown into operation and the machine will be stopped at a point in a cycle when the needle and awl are both out of the work and the presser foot is normally in work engaging 45 position. With the setting handle thus adjusted, the dog 472 will be released upon the rearward movement of the lock bolt carrier, and the presser foot will be lifted from the work when the machine is finally 50 brought to rest. The actuation of the bell crank 154 also opens the rear thread lock and releases the friction device from the tension wheel, so that the thread may be drawn freely through the wax pot in 55 moving the work from the machine.

To hold the shaft 454 securely in any one of the three positions in which it is adjusted by the operator, a plunger 500 mounted to slide in guides 502 in the frame, 60 and actuated by a compression spring 504

is arranged to engage any one of the three flat faces 506, 508 and 510 formed on a flange projecting from the shaft 454.

It is to be noted that the mechanism for stopping the machine, and for producing 70 the different predetermined conditions of the parts when the machine is stopped, is very easily and conveniently controlled by the operator, and that the operator at the time when he stops the machine, has to give 75 his attention only to the point in the work at which he desires to stop, the condition of the parts to be produced upon stopping the machine having been determined sometime before the stopping mechanism is 80 thrown into operation. The throwing in and out of the stopping mechanism is controlled from a treadle, so that the operator has both hands free to hold or manipulate the work at the time when the machine is 85 brought to rest.

Although the term awl has been employed in certain of the claims, applicant does not consider the invention defined in such claims as limited to the work piercing instrument 90 of a sewing machine which forms the holes in the leather for the passage of the needle, but believes that this term is broad enough to cover any other work penetrating instrument of a sewing machine such as the needle. 95

While the invention has been illustrated as embodied in a sewing machine having a straight hook needle and devices coöperating therewith to form a lock stitch, it is to be understood that except as defined in the 100 claims the features of the invention are not limited to any particular machine or type of machine. It is also to be understood that the invention is not limited to the particular construction of the illustrated embodiment of the invention, but that it may be embodied in other forms within the scope of the claims.

Having explained the nature and object of the invention, and having specifically described a machine embodying the same in its 110 preferred form, what is claimed is:—

1. A machine for operating on leather, having, in combination, means for operating on the work, devices for stopping the 115 machine at a predetermined point in a cycle of operations with the parts in either of two predetermined conditions, means for throwing the stopping devices into and out of operation, and means for setting said devices 120 so that when thrown into operation they will act to stop the machine with the parts in the desired condition.

2. A machine for operating upon leather, having, in combination, means for operating upon the work, automatically acting devices for stopping the machine and for causing the parts to assume either a normal or an abnormal condition when the machine is 125 stopped, and means for setting said devices 130

while they are inactive to stop the machine with the parts in the desired condition.

3. A machine for operating upon leather, having, in combination, means for operating upon the work, mechanism arranged to act automatically when thrown into operation to stop the machine and to cause the parts to assume either a normal or an abnormal condition when the machine is stopped, and means for controlling said mechanism.

4. A machine for operating upon leather, having, in combination, means for operating upon the work, mechanism arranged to act automatically when thrown into operation to stop the machine and to cause the parts to assume either a normal or an abnormal condition when the machine is stopped, and means under control of the operator for controlling said mechanism.

20 5. A machine for operating upon leather, having, in combination, means for operating upon the work, devices arranged to act automatically when thrown into operation for stopping the machine at a predetermined 25 point in a cycle of operations with the parts in either of two predetermined conditions, and means for setting said devices during the continued operation of the machine to stop the machine with the parts in the desired one of said conditions.

30 6. A machine for operating upon leather, having, in combination, means for operating upon the work, a main shaft, main driving mechanism therefor, means for connecting the driving mechanism with and disconnecting it from the shaft, devices thrown into operation when the shaft is disconnected from the main driving mechanism for stopping the machine with the parts in 40 either a predetermined abnormal condition or with the parts in another predetermined condition, and means for setting said devices so that when thrown into operation they will act to produce the required condition 45 of the parts when the machine is stopped.

50 7. A machine for operating upon leather, having, in combination, means for operating upon the work, devices for stopping the machine at a predetermined point in a cycle of operations, automatically acting means for causing the parts to assume either of two predetermined conditions when the machine is stopped at said point by the stopping devices, and mechanism for controlling said 55 last means.

60 8. A machine for operating upon leather, having, in combination, means for operating upon the work, devices for stopping the machine at a predetermined point in a cycle of operations, means for throwing the stopping devices into and out of operation, automatically acting means for causing the parts to assume either of two predetermined conditions when the machine is stopped at said

point by the stopping devices, and mechanism for setting said last means so that when thrown into operation they will act to produce the required condition of the parts when the machine is stopped.

9. A machine for operating upon leather, having, in combination, means for operating upon the work, devices for stopping the machine at either of two predetermined points in a cycle of operations, automatically acting mechanism for causing the parts to assume either a normal or an abnormal condition upon stopping the machine, and means for controlling both said devices and mechanism.

10. A machine for operating upon leather, having, in combination, means for operating upon the work, devices for stopping the machine at either of two predetermined points in a cycle of operations, automatically acting mechanism for causing the parts to assume either of two predetermined conditions upon stopping the machine at one of said points, and means for controlling both said devices and mechanism.

11. A machine for operating upon leather, having, in combination, means for operating upon the work, devices for stopping the machine at either of two predetermined points in a cycle of operations, means for throwing the stopping devices into and out of operation, automatically acting mechanism for causing the parts to assume either a normal or an abnormal condition upon stopping the machine, and means for setting both said devices and mechanism so that when thrown into operation they will act to stop the machine at the desired point and to produce the desired condition of the parts when the machine is stopped.

12. A machine for operating upon leather, having, in combination, means for operating upon the work, devices for stopping the machine at either of two predetermined points in a cycle of operations, means for throwing the stopping devices into and out of operation, automatically acting mechanism for causing the parts to assume either of two predetermined conditions upon stopping the machine at one of said points, and means for setting both said devices and mechanism so that when thrown into operation they will act to stop the machine at the desired point and to produce the desired condition of the parts when the machine is stopped.

13. A wax thread sewing machine, having, in combination, stitch forming devices, a work support, a presser-foot, means for lifting the presser-foot upon stopping the machine, mechanism for rendering said means active or inactive upon stopping the machine, and means for setting said mechanism while the presser-foot lifting means is in-

active to cause the presser-foot to assume the desired position when the machine is stopped.

14. A wax thread sewing machine, having, 5 in combination, stitch forming devices, a work support, a presser-foot, means for lifting the presser-foot automatically comprising a continuously vibrating actuating lever, a second lever, means for operatively connecting and disconnecting said levers, and connections between said second lever and the presser-foot.

15. A wax thread sewing machine, having, 15 in combination, stitch forming devices, a work support, a presser-foot, means for lifting the presser-foot automatically comprising a continuously vibrating actuating lever, a second lever, a dog carried by one of said levers for operatively connecting the levers, means for moving said dog into and out of operative position, and connections between the second lever and the presser-foot.

16. A wax thread sewing machine, having, 25 in combination, stitch forming devices, a work support, a presser-foot, means for lifting the presser-foot automatically comprising a continuously vibrating actuating lever, a second lever, means under the control of the operator for operatively connecting and disconnecting said levers, and connections between the second lever and the presser-foot.

17. A wax thread sewing machine, having, 35 in combination, stitch forming devices, a work support, a presser-foot, means for lifting the presser-foot automatically comprising a continuously vibrating actuating lever, a second lever, means for operatively connecting and disconnecting said levers, connections between said second lever and the presser-foot, and means for operatively connecting said levers upon stopping the machine.

45 18. A sewing machine, having, in combination, stitch forming devices, including an awl, a work support, a presser-foot, devices for stopping the machine with the awl out of the work and lifting the presser-foot automatically as the machine is stopped or stopping the machine with the awl out of the work and the presser-foot in lowered position and mechanism for controlling the action of said devices.

55 19. A sewing machine, having, in combination, stitch forming devices including an awl, a work support, a presser-foot, devices for stopping the machine with the awl out of the work and lifting the presser-foot automatically as the machine is stopped or stopping the machine with the awl in the work and the presser-foot lifted and mechanism for controlling the action of said devices.

20. A sewing machine, having, in combination, stitch forming devices including an awl, a work support, a presser-foot, mechanism for lifting the presser-foot automatically, devices for stopping the machine with the awl out of the work and the presser-foot in lowered position or stopping the machine with the awl in the work and the presser-foot lifter and the mechanism for controlling the action of said devices. 65

21. A sewing machine, having, in combination, stitch forming devices, a work support, a presser-foot, devices for stopping the machine at a definite point in a cycle of operations, mechanism arranged to act automatically to lift the presser-foot upon stopping the machine at said point and means for rendering said presser-foot lifting mechanism active or inactive when the machine is stopped at said point by the stopping devices. 75

22. A sewing machine, having, in combination, stitch forming devices, a work support, a presser-foot, means for lifting the presser-foot at a definite point during each cycle of operations, mechanism for lifting 90 the presser-foot upon stopping the machine at another point and means for rendering said mechanism active or inactive upon stopping the machine.

23. A sewing machine, having, in combination, stitch forming devices, a work support, a presser-foot, mechanism for lifting the presser-foot automatically upon stopping the machine and means for rendering said mechanism active or inactive upon stopping the machine. 95

24. A sewing machine, having in combination, stitch forming devices, including an awl, devices for stopping the machine with the awl out of the work or with the awl 105 in the work, means for throwing the stopping devices into and out of operation, and means for setting the stopping devices so that when thrown into operation they will act to stop the machine with the awl in the 110 desired position.

25. A sewing machine, having, in combination, stitch forming devices including an awl, a work support, a presser-foot, devices for stopping the machine with the awl out 115 of the work, mechanism for lifting the presser-foot automatically upon stopping the machine, and means for rendering the presser-foot lifting mechanism active or inactive.

26. A sewing machine, having, in combination, stitch forming devices including an awl, a work support, a presser-foot, devices for stopping the machine with the awl out of the work or with the awl in the work, 125 mechanism for lifting the presser-foot automatically upon stopping the machine with the awl out of the work, and means for

- rendering said presser-foot lifting mechanism active or inactive.
27. A sewing machine, having, in combination, stitch forming devices, including an awl, a work support, a presser-foot, devices for stopping the machine with the awl out of the work or with the awl in the work, and mechanism for lifting the presser-foot automatically upon stopping the machine 10 with the awl out of the work.
28. A sewing machine, having, in combination, stitch forming devices including an awl, a work support, a presser-foot, devices for stopping the machine with the awl out 15 of the work or with the awl in the work, and mechanism for lifting the presser-foot automatically upon stopping the machine.
29. A sewing machine, having, in combination, stitch forming devices including an 20 awl, a work support, a presser-foot, devices for stopping the machine with the awl out of the work or with the awl in the work, mechanism for lifting the presser-foot automatically upon stopping the machine and 25 means for rendering the presser-foot lifting mechanism active or inactive.
30. A sewing machine, having, in combination, stitch forming devices including an awl, a work support, a presser-foot, devices 30 for stopping the machine with the awl out of the work or with the awl in the work, means for throwing the stopping devices into and out of operation, mechanism for lifting the presser-foot upon stopping the 35 machine and means for setting the stopping devices so that when thrown into operation they will act to stop the machine with the awl in the desired position.
31. A sewing machine, having, in combination, stitch forming devices including an awl, a work support, a presser-foot, devices 40 for stopping the machine with the awl out of the work or with the awl in the work, means for throwing the stopping devices into and out of operation, mechanism for lifting the presser-foot automatically upon 45 stopping the machine arranged to be rendered active or inactive upon stopping the machine and means for setting the stopping devices and the presser-foot lifting mechanism so that when thrown into operation it will act to cause the awl and presser-foot 50 to assume the desired positions when the machine is stopped.
32. A sewing machine, having, in combination, stitch forming devices including an awl, a work support, a presser-foot, devices 55 for stopping the machine with the awl out of the work or with the awl in the work, mechanism for lifting the presser-foot automatically upon stopping the machine arranged to be rendered active or inactive upon 60 stopping the machine, and means for setting the presser-foot lifting mechanism while it is inactive to cause the presser-foot 65 to assume the desired position when the machine is stopped.
33. A sewing machine, having, in combination, stitch forming devices including an awl, a work support, a presser-foot, means 70 for lifting the presser-foot during each cycle of operations, devices for stopping the machine with the awl out of the work or with the awl in the work, and mechanism for lifting the presser-foot automatically 75 upon stopping the machine when the awl is out of the work.
34. A sewing machine, having, in combination, stitch forming devices including an awl, a work support, a presser-foot, means 80 for lifting the presser-foot during each cycle of operations when the awl is in the work, devices for stopping the machine with the awl out of the work or with the awl in the work, mechanism for lifting the presser-foot automatically 85 upon stopping the machine when the awl is out of the work, and means for rendering said mechanism active or inactive.
35. A sewing machine, having, in combination, stitch forming devices, a work support, a presser-foot, devices for stopping the machine at either of two predetermined points in a cycle of operations, and mechanism for lifting the presser-foot automatically 90 upon stopping the machine.
36. A sewing machine, having, in combination, stitch forming devices, a work support, a presser-foot, devices for stopping the machine at either of two predetermined 100 points in a cycle of operations, mechanism for lifting the presser-foot automatically upon stopping the machine, and means for rendering the presser-foot lifting mechanism active or inactive.
37. A sewing machine, having, in combination, stitch forming devices, a work support, a presser-foot, devices for stopping the machine, mechanism for lifting the presser-foot automatically upon stopping the machine, and means for rendering the presser-foot lifting mechanism active or inactive 105 while the stopping devices are active.
38. A machine for operating upon leather, having, in combination, means for operating upon the work, devices for stopping the machine at either of two predetermined points in a cycle of operations, means for causing the parts of the machine to assume a normal condition when the machine is stopped at one of said points by the stopping devices, and to assume either a normal or an abnormal condition when the machine is stopped at the other of said points, and mechanism for controlling the stopping devices and said means. 115
39. A machine for operating upon leather having, in combination, means for operating upon the work, devices for stopping the machine at a predetermined point in a cycle 120
- 125
- 130

of operations with the parts in either of two predetermined conditions, and means for reducing the speed of the machine to a predetermined speed before the stopping devices are rendered active.

40. A machine for operating upon leather having, in combination, means for operating upon the work, devices for stopping the machine and for causing the parts to assume either a normal or abnormal condition when the machine is stopped, and means for rendering said devices active when the speed of the machine has been reduced to a predetermined speed.

41. A machine for operating upon leather having, in combination, means for operating upon the work, devices for stopping the machine at a predetermined point in a cycle of operations, automatically acting means for causing the parts to assume either of two predetermined conditions when the machine is stopped at said point by the stopping devices, and mechanism for rendering said devices active when the speed of the machine has been reduced to a predetermined speed.

42. A machine for operating upon leather having, in combination, means for operating upon the work, devices for stopping the machine at either of two predetermined points in a cycle of operations, automatically acting mechanism for causing the parts to assume either a normal or an abnormal condition upon stopping the machine, and means for rendering said devices active when the speed of the machine has been reduced to a predetermined speed.

43. A machine for operating upon leather having, in combination, means for operating upon the work, devices for stopping the ma-

chine at either of two predetermined points in a cycle of operations, automatically acting mechanism for causing the parts to assume either of two predetermined conditions upon stopping the machine at one of said points, and means for rendering said devices active when the speed of the machine has been reduced to a predetermined speed.

44. A machine for operating upon leather having, in combination, means for operating upon the work, devices for producing automatically an abnormal condition of the parts upon stopping the machine, and means for rendering said devices active or inactive upon stopping the machine.

45. A machine for operating upon leather having, in combination, means for operating upon the work, devices for producing automatically an abnormal condition of the parts upon stopping the machine, and setting mechanism adapted to be adjusted while said devices are inactive to render said devices active or inactive upon stopping the machine.

46. A machine for operating upon leather having, in combination, means for operating upon the work, a main shaft, driving mechanism for the shaft, devices arranged to be thrown into operation upon disconnecting the driving mechanism from the shaft for producing an abnormal condition of the parts, and controlling mechanism for rendering said devices active or inactive upon disconnecting the driving mechanism from the shaft.

LAURENCE E. TOPHAM.
